UNITED STATES PATENT OFFICE.

GEORGE W. SMITH, OF FORBES, NORTH DAKOTA.

PAIL.

Application filed January 12, 1927. Serial No. 160,701.

This invention relates to pails and has for its object the production of a simple and efficient pail which is provided with an annular flange of substantial width upon the top edge thereof to facilitate the holding of the pail upon the knee of the milker, while milking.

Another object of this invention is the production of a simple and efficient pail which is reinforced by means of the substantially wide and annular rim around the upper edge thereof, which rim facilitates the pouring of liquids from the pail.

Other objects and advantages of the present invention will appear throughout the following specification and claims.

In the drawings:

Figure 1 is a side elevation of a pail,

Figure 2 is a vertical section through the pail, taken at right angles to Figure 1, and

Figure 3 is a top plan view of the pail.

By referring to the drawings, it will be seen that 1 designates the body of the pail which tapers toward its lower end as clearly illustrated in the drawing, and terminates at its upper edge in a substantially wide laterally extending annular rim 2 formed integral with the body 1 of the pail. A pair of vertically extending tongues 3 are struck from the rim or flange 2 so as to extend substantially in line with the side walls of the pail. The handle 4 is journaled upon the ears 3 by having the ends 5 thereof extending through suitable apertures 6 formed in the ears 3, as clearly illustrated in the drawings.

From the foregoing description, it will be seen that a very simple bucket or pail has been produced which may be formed of

metal or any other suitable material, the same being formed all of one piece and being provided with a reinforcing substantially wide and straight annular flange at its upper edge, from which flange in alignment with the side walls of the pail extend the handle 45 engaging ears, in this way producing a very rigid structure.

It should be understood that certain detail changes in the mechanical structure and design may be employed without departing 50 from the spirit of the invention, so long as these changes fall within the scope of the appended claims.

Having described the invention, what is claimed is:

1. As a new article of manufacture, a pail comprising a body having a substantially wide annular rim formed upon the upper edge thereof, a plurality of ears struck from said rim and extending substantially in line 60 with the walls of the pail, and a handle having its ends extending through said ears for constituting a carrier for said pail.

2. A pail of the character described, comprising a body having the side wall thereof tapering toward the bottom, an integral annular flange surrounding the upper edge of said body, a pair of apertured ears struck from said flange and arranged to extend upwardly from and substantially in alignment 65 with a wall of said pail, said ears being arranged at diametrically opposite points, and a bail handle having the ends thereof each engaged through one of said apertured ears, substantially as described.

In testimony whereof I affix my signature.

GEORGE W. SMITH.
